(57) CLAIM

The ornamental design for the thumb insertion portion of a baseball mitt, as shown and described.

DESCRIPTION

FIG. 1 is a front elevational view thereof of my new design; FIG. 2 is rear elevational view thereof; FIG. 3 is a right side elevational view thereof; FIG. 4 is a left side elevational view thereof; FIG. 5 is a bottom view thereof; and, FIG. 6 is a perspective view thereof.

The broken-lines showing the environmental parts of the thumb insertion portion in the figures are for illustrative purpose only, and form no part of the claimed invention. The broken-lines appearing in the thumb insertion portion illustrate the stitching provided thereon.
